CLAIM

The ornamental design for a pellet grill body, as shown and described.

DESCRIPTION

FIG. 1 is an isometric view within the environment of a pellet grill body;

FIG. 2 is an isometric front view;

FIG. 3 is an isometric back view;

FIG. 4 is a front view;

FIG. 5 is a back view;

FIG. 6 is a left side view;

FIG. 7 is a right side view;

FIG. 8 is a top view; and,

FIG. 9 is a bottom view.

The broken lines showing the environment of a pellet grill and portions of the pellet grill body form no part of the claimed design.
